UNITED STATES PATENT OFFICE.

SEBASTIAN ZIANI DE FERRANTI, OF HOLLINWOOD, ENGLAND, ASSIGNOR TO FERRANTI, LIMITED, OF HOLLINWOOD, ENGLAND.

ELECTRIC TRANSFORMER.

Application filed February 11, 1926, Serial No. 87,690, and in Great Britain November 6, 1924.

This invention relates to electric transformers and more particularly to small audio frequency transformers for use in connection with wireless telephony, and has for its object to provide improved or simplified constructions.

Referring to the accompanying diagrammatic drawings:—

Figure 1 is a vertical sectional view of a convenient construction in accordance with the present invention.

Figure 2 is a vertical sectional view taken at right angles to that according to Figure 1.

Figure 3 is a side elevational view with one of the primary terminal nuts removed for clearness.

Figure 4 is a plan view.

In carrying the invention into effect in one form by way of example, I form a casing of two identical pressings *a*, *a*, of thin sheet metal, these pressings being formed with rims *b*, *b* to impart lateral rigidity. To the base of each pressing two further pressings *c*, *c* of channel shape and of preferably heavier gauge metal are attached, conveniently by spot welding or riveting, the casing pressings being reinforced at this region by means of angle pieces *d*, *d* also spot welded or riveted to the casings. The two pairs of channel pressings serve as feet for supporting the casing, and each is perforated at *e*, *e*. The core comprises a plurality of laminæ *f*, which when erected form one central limb and two return limbs, those on the outer sides of the core being slightly smaller than the inner ones (see Figure 2) first to enable the center limb of the core to pass through the circular or approximately circular hole through the bobbins and also to enable the core to fit within the casing which at the corners has a radius; if the stampings were all of the same size at the exterior the casing pressings would require perfectly square corners. The primary and secondary windings of the transformer are disposed upon the central limb, each winding being preferably formed of four separately wound bobbins connected in series electrically. A connecting lead is taken from the two extreme ends of the primary and secondary windings. The primary leads are connected respectively to two terminals *j* mounted in a primary terminal block *l*, and the secondary leads are similarly connected

to terminals *k* in a secondary terminal block. These blocks, which are formed of insulating material (preferably moulded ebonite or similar materials), are each provided with two thin metal strips *o* and *p* respectively 60 bent over and attached at one end to the block, the purpose of these strips being to support the terminal blocks temporarily, as explained below. Each terminal is provided with a central longitudinal hole extending 65 through its entire length, to enable the leads to be brought through these holes and to be soldered finally at *q* to the tips of the terminals. One limb of each strip is adapted 70 to rest behind a few of the outermost core laminæ, and thus to support the terminal blocks flush against the outermost core laminæ, a sheet of insulating material *r* being interposed at this point as regards the 75 secondary terminal block, but as regards the primary terminal block I insert at this point a condenser *s* appropriate to the characteristics of the transformer and the uses to which it is to be put. This condenser conveniently comprises two or more thin conducting 80 plates separated by a sheet of dielectric material and each provided with a cranked tang. A further sheet of insulating material is provided above and below the thin 85 conducting plates and each of the tangs is slit for the insertion of and soldering thereto of the conducting leads from the two extreme ends of the primary winding. The condenser as a whole is bound with a sheet 90 of paper or the like and is inserted between the primary terminal block *l* and the outermost core laminæ which this block abuts. The moulded terminal blocks are thus provisionally attached to the transformer proper, being permanently connected to the windings 95 by short leads, the moulded blocks and terminals and condenser (if used) being all finally clamped firmly together and held in position by the casing when the latter is clamped together. 100

The terminals may be moulded in individual blocks or preferably in common blocks as regards primary and secondary and are so arranged that a portion or portions of the insulation projects or project through holes 105 in the casing, these portions thus insulating the terminal stems giving a sufficiently long leakage path.

Alternatively, the condenser may be moulded in the primary terminal block in- 110

stead of being fitted behind it as described above.

Each casing pressing *a*, *a* is formed with two openings which enable these pressings to be applied back to back and being so arranged that the four terminals and portions of the terminal blocks protrude through the holes. The two casing pressings are clamped together by bolts *s*' and nuts *t*. The 10 bolts, however, do not require to pass through the core laminæ and when bolted together the pressings not only clamp the laminæ firmly, but also clamp the terminal blocks and prevent any possible displacement thereof.

It will be understood that when so clamped the thin supporting strips have no function, being provided solely as temporary supporting means prior to the fitting of 20 the pressings. The casing portions, however, may be removed entirely to give access to the transformer proper without disturbing the terminals, connecting leads and primary shunting condenser (if provided).

25 After the transformer has been erected I prefer to attach a number plate (not shown) within the channel formed by one of the pairs of feet, this conveniently being effected by means of eyelets, the number 30 plate besides providing means of identification serving to prevent the transformer from

being dismantled without breaking of the number plate.

Having now described my invention, what I claim as new and desire to secure 35 by Letters Patent is:—

1. An audio frequency electric transformer embodying a self-contained unit including a laminated core, coils on said core, terminal blocks connected to said coils and 40 provisionally supported by the laminæ of said core and a two-part perforated metal casing, which latter when clamped in position entirely encloses and maintains said unit rigidly in position with the terminals 45 projecting through perforations in the casing parts.

2. An audio frequency electric transformer as claimed in claim 1, wherein the two-part perforated metal casing comprises 50 thin sheet metal pressings to which are fastened channel feet of preferably heavier gauge, the pressings being reinforced at the regions of attachment of the feet.

3. An audio frequency electric transformer as claimed in claim 1, including an appropriate condenser incorporated as part of the self-contained unit.

In testimony whereof I have signed my name to this specification.

SEBASTIAN ZIANI DE FERRANTI.
